R. C. CARVER

ADJUSTABLE ANGLE WRENCH

Filed Jan. 29, 1925

INVENTOR.

Ray C. Carver.

BY

P. H. Gallenbach
ATTORNEY.

UNITED STATES PATENT OFFICE.

RAY C. CARVER, OF GRAND JUNCTION, COLORADO.

ADJUSTABLE ANGLE WRENCH.

Application filed January 29, 1925. Serial No. 5,514.

To all whom it may concern:

Be it known that I, RAY C. CARVER, a citizen of the United States of America, residing at Grand Junction, in the county of 5 Mesa and State of Colorado, have invented certain new and useful Improvements in Adjustable Angle Wrenches, of which the following is a specification.

This invention relates to a wrench, the 10 jaws of which are removable and interchangeable, and has for its principal object the provision of a wrench of this character in which the angle of projection of the jaws can be quickly and easily adjusted.

15 Another object of the invention is to provide a wrench of this character in which the wrench jaws may be easily removed and replaced.

20 A further object resides in the novel means employed for attaching, without the use of screws, bolts, nuts, etc., the wrench jaws to the wrench handle.

A still further object is to so construct a 25 flat jawed wrench that it may be readily transformed into a socket wrench.

Other objects and advantages reside in the detail construction of the invention, which result in simplicity, economy, and efficiency, and which will become more apparent from the following description.

In the following detailed description of the invention reference is had to the accompanying drawing which forms a part hereof. Like numerals refer to like parts in all 35 views of the drawing and throughout the description.

In the drawing:

Fig. 1 is an edge elevation of my improved wrench, partly broken away to illustrate the interior construction thereof;

Fig. 2 is a face elevation of the same;

Fig. 3 is a detail view of the wrench engaging extremity of the handle;

Fig. 4 is a detail view of one form of 45 wrench jaw which may be used in connection with my improved wrench;

Fig. 5 is a detail view of the retaining washer employed to secure the wrench jaws to the handle;

Fig. 6 is a detail view of another form 50 of wrench jaw which may be used in conjunction with my improved handle; and

Fig. 7 is a perspective view of the means employed when it is desired to attach a 55 socket wrench to my improved handle.

The invention comprises a handle 10, cut

away at its one extremity to form a wrench seat 11. Concentrically projecting from the wrench seat 11 is a wrench post 12, provided near its extremity with an annular 60 groove 13. Slidably mounted within the handle 10 is a pawl 14 actuated by means of a spring 15. Formed on the pawl 14 is a knurled finger rest 16.

In conjunction with the handle 10, I employ wrenches such as illustrated in Figs. 4, 6 and 7. The wrench in Fig. 4, designated by the numeral 20, is one of the usual type of flat wrenches. That in Fig. 6, designated by the numeral 21, is one of the usual type 70 of side outlet wrenches. Fig. 7, illustrates, what might be termed, a socket holder 17 carrying a square post 18 for engagement in the square socket of any of the usual types of socket wrenches 19. Each of the wrenches 75 20 and 21 and the socket holder 17 is provided with an opening 22 designed to fit over the post 12 and with peripheral notches 23 designed to be engaged by the extremity 80 of the pawl 14.

The wrenches are held in position on the wrench post 12 by means of a retaining washer 24 carrying a radially extending slot 25. After a wrench has been placed over the wrench post 12, the retaining washer 24 85 is slid over the wrench, the peripheral groove 13 engaging the edges of the slot 25.

When the retaining washer 24 is being placed on, or removed from, the wrench post 12, the slot 25 will occupy the broken 90 line position indicated at 26, Fig. 2. When in this position, the retaining washer may be easily removed in the direction of the axis of the handle 10. The washer is locked in place by giving it a turn so as to move the 95 slot 25 away from the axis of the handle 10 as illustrated in the full line position of Fig. 2. When the slot 25 is in any other position than that of the broken line position 26, it will be impossible for the retaining washer 24 to become disengaged since any angular movement will be prevented by curved shoulders 27 on the handle 10, bordering the wrench seat 11. By this arrangement, the retaining washer is firmly 100 locked in its position until the operator desires to change wrenches, when it can be easily removed without the use of tools.

In Figs. 1 and 2, the wrench 20 is illustrated in alignment with the handle 10. Should it be desired to have the wrench project at an angle from the handle, so as to

more conveniently reach the work, the pawl 14 is operated by means of a finger rest 16 so as to compress the spring 15 and withdraw the pawl from the notch 23. The 5 wrench may now be turned to the desired position, such as one of those illustrated in broken lines, Fig. 2.

The handle 10 may be knurled as illustrated at 28 to give a more efficient hand 10 hold if desired.

While a specific form of the improvement has been described and illustrated herein it is desired to be understood that the same may be varied, within the scope of the appended 15 claims, without departing from the spirit of the invention.

Having thus described the invention, what I claim and desire to secure by Letters Patent is:—

- 20 1. A wrench comprising a handle; a wrench seat formed at one end of said handle; a wrench post projecting from said seat, said post being provided with an annular groove; a wrench jaw arranged to be 25 fitted over said post against said seat and means for securing said wrench on said seat, said means comprising a washer having a radial slot the edges of which are adapted to engage in said annular groove in said 30 post.
2. In a wrench comprising a handle, a detachable wrench jaw arranged to rotate on

said handle and a pawl arranged to engage said jaw to retain it at any desired angle, the combination of means for securing said wrench jaw to said handle, said means comprising a pivot post provided with a groove and adapted to pass through said wrench jaw, a washer provided with a slot adapted to be carried on said post with said 40 slot engaging said groove, and a projection on said handle for preventing the removal of said washer from said post except when the former is in a predetermined 45 position.

3. In a wrench having an angularly adjustable and detachable wrench member secured to a handle, means for locking said wrench member to said handle comprising a depressed circular face in said handle for receiving said wrench member; a pivot post concentrically arranged in said face and adapted to pass through said wrench member; a radially slotted washer adapted to be slid into engagement in a circumferential slot in said pivot post to maintain said wrench member thereon; and a curved shoulder at one side of said face acting to allow said washer to be moved longitudinally of said handle and preventing angular movement thereof.

In testimony whereof, I affix my signature.

RAY C. CARVFR.
